BICYCLE EXERCISER OR THE LIKE

Eugene Weiss, Merrick, N.Y., assignor to Beacon Enterprises, Inc., New York, N.Y., a corporation of New York

Filed Nov. 17, 1966, Ser. No. 4,720

Term of patent 14 years

(Cl. D34—5)

FIG. 2

FIG. 1 is a perspective view of a bicycle exerciser showing my new design, and

FIG. 2 is a top plan view thereof with broken line portions for the seat and pedals omitted for convenience of illustration.

The dominant features of the design reside in the portions shown in full lines.

I claim:

The ornamental design for a bicycle exerciser or the like, substantially as shown and described.
